Steve DeRosa,
INVENTOR
BY Victor J. Evans

ATTORNEY

UNITED STATES PATENT OFFICE.

STEVE DE ROSA, OF BROOKLYN, NEW YORK.

WINDOW-CLEANING DEVICE.

Application filed December 10, 1926. Serial No. 153,941.

This invention relates to improvements in window cleaning devices.

The primary object of the invention resides in a device for cleaning the outside 5 of a glass window pane without necessitating a person risking injury or life by standing or sitting upon a window sill to reach the surface to be cleaned.

Another object of the invention is to provide a window cleaning device which is automatic in its action when applied to the window casing of a window to be cleaned so as to dispense with the usual labor of applying water to the glass pane to be 15 cleaned and then drying the pane.

A further object of the invention is the provision of a window cleaning device which automatically applies water to the pane to be cleaned upon sliding movement of a 20 window sash in one direction and for thoroughly drying the pane upon movement of the sash in the opposite direction.

A still further object of the invention is to provide a window cleaning device of the 25 class mentioned which is easy to apply to a window or removed therefrom, simple of construction, and thorough of operation.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved window cleaning device per se.

Figure 2 is a horizontal sectional view 40 through a window showing the device in position thereon.

Figure 3 is a vertical sectional view therethrough showing a moistening element in engagement with the window.

Figure 4 is a similar view but showing 45 the position of the parts with the squeegee in engagement with the glass pane.

Figure 5 is a vertical sectional view on the line 5—5 of Figure 2.

Figure 6 is a detail perspective view of 50 the moistening element removed from its holder.

Figure 7 is a detail horizontal sectional view showing the manner of holding the de-

vice to a window casing for cleaning an upper sash.

Figure 8 is a detail front elevational view of one of the end brackets.

Referring more particularly to the drawings, the reference numeral 10 designates my improved window cleaning device in its entirety and which includes an elongated bar 11 which supports brackets 12, 12 at opposite ends and which brackets extend from the bar for turnably supporting moistening means 13 and drying means 14.

The moistening element 13 comprises a holder 15 which is of a length to fit between the brackets 12, 12 and which is constructed of metal and provided with a socket 16 to frictionally receive a removable moistening element 17 in the nature of a piece of cloth composed of a plurality of layers of material, or the same may be a strip of felt so as to hold water when dipped therein, and which element is saturated before placing 65 the same in the holder for use. The holder 15 has pintles 18 which have their bearings in the brackets 12 and which have gear segments 19 fixedly mounted thereon. Wheels 20 are freely mounted on the pintles 18 and

have a rubber tire or tread surface 21 which projects beyond the front of the brackets for contact with the vertical rails of a window sash in a manner to be presently explained. The wheels 20 are under tension to cause 75 them to normally rotate with the gear segment 19, by reason of flat springs 22 which bear against the inner side faces of the wheels 20. However, when the force to rotate the wheels overcomes the tension of the springs, the wheels will rotate irrespective of the gears for a purpose to be presently explained.

The drying means 14 comprises a holder 23 which supports a strip of relatively stiff 80 flexible material 24 such as a strip of rubber and which constitutes a squeegee. The holder 23 has its ends provided with ears 25 which are connected with stub shafts 26 having bearings in the brackets 12 to one side 85 of the vertical axis of the pintles 18. The stub shafts have gear segments 27 fixed thereon for constant meshing engagement with the gear segments 19 whereby movement is transmitted from the gear segments 19 to the gear segments 27 to move the 90

squeegee into engagement with the window glass to be wiped after the application of water thereto by the moistening element.

In Figures 2, 3 and 4, I have shown my invention applied to a window W which includes a window casing C having vertical parting strips P and P' within which the upper and lower sashes U and L are slidably mounted. For the purpose of rigidly supporting the cleaning device with respect to the sash for cleaning the outside of the glass pane G, I provide attaching means 28 at opposite ends of the device and which means comprises spaced rails or tracks 29 provided 10 on the brackets 12 and which slidably receive clamps 30 which have dove-tail grooves 30' for receiving the dove-tail tracks 29. The clamps include U-shaped jaws 31 for receiving the parting strip P for rigidly 20 clamping the device thereon. A set screw 33 is threaded in the brackets and serves as a stop for the clamp to prevent sliding movement of the same with respect to the brackets when in an adjusted position upon 25 the window casing.

In operation, the device is clamped on the parting strip P when it is desired to clean the outside of the window pane G of the lower sash L and it is attached by inserting 30 the U-shaped clamps over the parting strip at a point adjacent the meeting rails of the upper and lower sashes and thence tightening up upon the clamping screws 32. It will be understood that it is first necessary 35 to wet the moistening element and insert the same in its holder and to raise the lower sash to mount the device upon the window casing. When in position as shown in Figure 3 of the drawings, the rubber tires of the 40 wheels 20 are tight against the vertical rails R of the lower sash with the moistening element 17 bearing against the outside surface of the pane and completely spanning the same from one side rail to the other. 45 The lower sash being in a raised position, is now manually lowered to slide downward and as it moves down the tendency of the same is to rotate the wheels 20, which being under tension serve to forcibly press the 50 moistening elements against the window pane to wet the pane and wipe off any dirt or dust which might be present thereon. Should the friction between the wheels 20 and the window sash overcome the tension 55 of the flat springs 22, the wheels will slip or turn but will still maintain a pressure upon the moistening element. As the sash reaches the limit of its downward movement and the entire length of the window glass has 60 been washed, the operator manually raises the sash, and in so doing, causes a reverse rotation of the wheels 20 which operates the gear segments 19 and 27 to cause the moistening element to swing outward away from 65 the glass and automatically swings the

squeegee or wiping element into contact with the same. As the sash moves upward, the rubber squeegee wipes the glass pane free of all water which may have been left thereon by the moistening element. It will 70 therefore be seen that the window pane is thoroughly cleaned by the movement of the sash back and forth without manual labor on the part of an operator other than that necessary to raise and lower the sash. 75 When cleaning the upper sash U, the clamps 31 are removed and the set screws 33 tightened against the window casing as shown in Figure 7 of the drawings.

For locking the parts against movement 80 when not in use, I provide a sliding bolt 34 on one end of the squeegee holder 23 which is movable into a recess 35 provided in the inner wall of the adjacent bracket.

From the foregoing description it will be 85 seen that I have provided a window cleaning device which may be applied to a window of a given size to thoroughly clean the same by merely sliding the sashes up and down, but which device may be constructed 90 of various sizes to fit the standard size sashes.

While I have described what I deem to be the most desirable embodiment of my invention, it is obvious that many of the details may be varied without in any way departing from the spirit of my invention, and I therefore do not limit myself to the exact 95 details of construction herein set forth nor to anything less than the whole of my invention limited only by the appended 100 claims.

What is claimed as new is:—

1. In combination with a window casing having a sash slidably mounted therein, of a cleaning device including moistening means, drying means, and means operable by said window sash for alternately causing said moistening means and said drying means to engage the glass pane of said sash 110 upon sliding movement of said sash in opposite directions.

2. In combination with a window casing having a sash slidably mounted therein, a window cleaning device including attaching means thereon for rigidly mounting said device upon said window casing with respect to said sash, a movable moistening element, a movable scraping element, actuating means for simultaneously moving the elements in 120 opposite directions toward and away from the glass pane of said sash, and means operable by said sash for controlling said actuating means and for holding said elements tight against the glass pane as they 125 respectively engage the same.

3. In combination with a window casing, a sash slidably mounted therein and having a glass pane, a cleaning device including means for removably attaching said device 130

to said window casing, a moistening element of a length equal to the width of said pane, a scraping element of a length equal to the width of said pane, and means operable by 5 said window sash for alternately causing said moistening element and said scraping element to engage said pane upon sliding movement of said sash in opposite directions.

10 4. A window cleaning device comprising a pair of spaced brackets, a pair of cleaning elements journaled therein for swinging movement, a friction wheel adapted to engage a window sash, and means operable by 15 said friction wheel for imparting opposite swinging movements to the respective cleaning elements upon movement of the window sash in opposite directions.

5. A window cleaning device comprising 20 attaching means for removably mounting the device upon a window, a pair of spaced brackets, a holder journaled in said brackets for swinging movement, a moistening element removably supported by said holder, 25 a flexible scraper element turnably mounted in said brackets, and means adapted to be operated by the up and down movements of a window sash for simultaneously turning said holder and said scraping element in 30 opposite directions upon reverse movements

of the window sash and for maintaining the same in position during the movement of the same in the respective directions.

6. A window cleaning device comprising 35 an elongated bar, a pair of brackets mounted on the ends of said bar, a moistening element having pintles journaled in said brackets for turning movement, a flexible scraping element turnably mounted in said brackets, friction slip wheels mounted on said 40 pintles and having their peripheral edges extending beyond one side of said brackets for engagement with a sliding window sash, co-acting gears operable by said friction slip wheel to move the moistening elements 45 simultaneously in opposite directions, and attaching means carried by said brackets for removably attaching the device to a window casing.

7. A window cleaning device comprising 50 a pair of swingingly mounted cleaning elements, and means adapted to be operated by the movements of a window sash to alternately move the respective cleaning elements into operative and inoperative positions, and means for locking said cleaning elements against movement when not in use. 55

In testimony whereof I have affixed my signature.

STEVE DE ROSA.
